UNITED STATES PATENT OFFICE.

VIRGIL K. BROWN, OF BRYAN, OHIO.

DESIGN FOR A MATCH-SAFE, &c.

SPECIFICATION forming part of Design No. 18,706, dated October 30, 1888.

Application filed September 21, 1888. Serial No. 286,043. Term of patent 7 years.

To all whom it may concern:

Be it known that I, VIRGIL K. BROWN, a citizen of the United States, residing at Bryan, in the county of Williams and State of Ohio, have invented and produced a new and original Design for Tooth-Pick and Match Holders; and I do hereby declare the following to be a full, clear, and exact description of the same, reference being had to the accompanying drawing, forming a part thereof.

The drawing, consisting of a single figure, represents a perspective view of my design, which is in the form of a parallelopiped having twin truncated elevations A A, in each of which there is constructed an orifice, B B, of suitable depth and proportions to form a receptacle for matches, tooth-picks, or ink. The polished surface of the material, C C C C, is left undisturbed on the top about the edges of the orifices and on the ends and back, also on the border about the space containing the

legend; but on the front the surface is cut away in a space forming a parallelogram panel suitable for a legend. The edges about this panel present the polished surface of the material and form a symmetrical border. The portions cut away are designed to remain unpolished, so as to present a contrast with the uncut and unpolished portions. 25

What I claim is—

The design of a match-safe and tooth-pick holder herein shown and described, the same comprising a parallelopiped having twin truncated elevations A A and the orifices B B therein, with a depressed space for a legend and border on its front. 30

In testimony whereof I affix my signature in presence of two witnesses.

VIRGIL K. BROWN.

Witnesses:

C. E. SCOTT,
ENOS McELHINEY.
